Inventor

Joseph W. Prall

UNITED STATES PATENT OFFICE.

JOSEPH W. PRALL, OF POMEROY, OHIO, ASSIGNOR OF THREE-FOURTHS TO
W. G. DOWNIE, OF SAME PLACE.

LOCK-CAP CLEATLESS ROOFING.

SPECIFICATION forming part of Letters Patent No. 397,093, dated January 29, 1889.

Application filed December 15, 1888. Serial No. 293,682. (No model.)

To all whom it may concern:

Be it known that I, JOSEPH W. PRALL, a citizen of the United States, residing at Pomeroy, in the county of Meigs and State of Ohio, have invented certain new and useful Improvements in Lock-Cap Cleatless Roofing; and I do hereby declare the following to be a full, clear, and exact description of the invention, such as will enable others skilled in the art to which it appertains to make and use the same.

My invention has for its object the ready attachment and removal of its parts or sections, the facility for fastening the same without the use of cleats, and the prevention of any leakage from snow or rain water; and it consists of a certain peculiar and novel joint, which for convenience I style "lock-cap," for connecting the metallic sheets or plates at their edges, all of which will more fully appear from the following description.

In the drawings, Figure 1 shows a plan of the joint made according to my invention, and Fig. 2 a cross-section of the same.

25 A indicates the metal sheet or plate, which is formed on each side with open box-like portions B C, having the bends d e f and the inclined portions g, and made by bending the metal on forms, and which portions B C are 30 made of substantially the same shape or contour and adapted to fit snugly one over the other to make a tight joint, the natural spring of the metal and the peculiar bends employed being sufficient to securely fasten the plates 35 or sheets together. In the portion C, running from the outer inclined portion g, is a flat horizontal portion, h, on a plane with the sheets, and which is adapted to be nailed or otherwise fastened to the roof or other place 40 to be covered to hold the roofing to place.

The operation of my invention will be clearly understood. I take a sheet or plate, No. 1, of any desired size and having my improved lock-caps thereon, and nail or otherwise secure the strip h to the place to be covered. I then take another one of my improved

plates, No. 2, and by pressure spring the portion B over the already-fastened portion C, and then proceed to nail the other side of sheet No. 2, and so on until the place is covered.

It is obvious that other designs of curved bends may be employed and still be efficient for practicing my invention; but I prefer the three-leaf-clover style, as shown, for general 55 purposes.

It will readily be seen that by using my lock-cap leakage is impossible, even if the snow was piled high upon the roof.

It will also be seen that my invention is applicable to sidings and ceilings as well as roofs, and may be applied and removed with equal facility wherever it may be placed.

I prefer to employ steel or iron plates or sheets in practicing my invention; but any 65 metal having sufficient spring may of course be used.

It will also be seen that no acute angles are used, where dirt can collect and water settle and rust the metal.

I claim—

1. Metallic roofing consisting of the plates or sheets A, each sheet being formed with the bent curved portions B C, each of these portions being made with the substantially semi-circular bends d e f and inclined portions g, the portion C having also the extension h, these portions B C being adapted by reason of the bends to lock each other and to be fastened to a base by means of the portion h. 75

2. A lock-joint for metallic roofing, consisting of two portions, each of which has substantially semi-cylindrical bends similarly disposed, and also the inclined portions g, and adapted to be sprung one upon the other, 85 for the purpose described.

In testimony whereof I affix my signature in presence of two witnesses.

JOSEPH W. PRALL.
